POWER DIPPER TRIP

Filed Sept. 19, 1930

FIG. 2.

FIG. 1.

INVENTOR.

Alvin W. Anderson

BY *Lancaster, Allwine and Cornwell*
ATTORNEYS.

UNITED STATES PATENT OFFICE

ALVIN W. ANDERSON, OF FREEPORT, ILLINOIS

POWER DIPPER TRIP

Application filed September 19, 1930. Serial No. 483,075.

The present invention relates to power shovels and more particularly to improved means for tripping the bottoms or doors of dippers or buckets of power shovels.

5 The primary object of the invention is to provide a power operated dipper trip for power shovels.

A further object is to provide a fluid pressure operated device of this character adapted to be controlled thru the operation of a valve disposed in a readily accessible location to the operator of the shovel.

15 A further object of the invention is to provide a simple trip releasing device susceptible of mounting upon the boom of existing types of power shovels for exerting a pull upon the trip cable or line to release the dipper bottom.

20 A further object resides in the novel manner of controlling the fluid pressure operated trip lever to permit slack in the trip cable, and also the improved means for limiting movement of the trip lever when a pull is exerted upon the cable.

25 Other objects and advantages of this invention will be apparent from the following detailed description, taken in connection with the accompanying drawings and in which drawings:

30 Figure 1 is a side view of a conventional type of power shovel boom and showing the invention applied thereto.

Figure 2 is an enlarged side plan view 35 part in section and part in elevation of the device as applied to the boom.

Figure 3 is a top plan view of Figure 2.

Referring to the drawings in detail and wherein similar reference characters designate corresponding parts thruout the several views, the improved dipper trip device has been shown applied by way of example to a typical type of shovel trip mechanism such as disclosed in Patent Number 1,439,216 granted December 19, 1922.

45 In the drawings, the power shovel mecha-

nism is of typical construction and embodies the boom 5 pivotally mounted at its lower end upon the turntable 6 which also supports the driving or power means, not shown, enclosed by the usual cab 7 from which the operator controls movement of the dipper 8. The dipper 8 is supported upon the dipper stick or shipper shaft 9 which operates thru the boom 5 for retracting and extending the dipper, and the usual hoisting cable 10 is provided for raising and lowering the dipper. Pivotally mounted at the lower end of the dipper is the usual swinging door or bottom 11 held in a closed position by a latch, not shown, having connection with a latch lever 12 pivotally carried by the dipper stick 9.

Connected with the free end of the latch lever 12 is one end of a latch line or tiller rope 13 which extends about a sheave 14 carried by a swinging lever 15 pivoted upon the boom 5 and is wound upon a drum or spool 16 rotated by movement of the dipper stick 9. In operation of the device thus far described, when the dipper stick is either extended or retracted, the spool 16 is rotated for either winding or unwinding the tiller rope 13 in accordance with the movement of the dipper stick and taking up slack in the tiller rope.

75 In this manually operated type of trip mechanism, a pull line is connected to the free end of the swinging lever 15 and extends to a location in the cab 7 within reach of the operator so that when a pull is exerted upon the pull line the dipper bottom will be tripped. The present invention relates to an improved fluid pressure operated means for exerting a pull upon the pull line.

80 Referring now to the power operated means forming the subject matter of the present invention, the same embodies a fluid cylinder 20 attached by suitable brackets 21 to the upper or outer end of a mounting plate 22 secured longitudinally upon one side of 85

90

the boom 5 rearwardly of the swinging lever 15. The mounting plate 22 may be secured to the boom as by bolts or rivets 23 as shown. Operating within the cylinder 20 is a piston 24 to which is pivotally connected one end of a piston rod 25 that projects rearwardly beyond the open rear end of the cylinder. The rear end of the piston rod 25 is pivotally connected as at 26 to the intermediate portion of a trip lever 27 pivotally mounted at its lower end as at 28 upon the mounting plate 22. This trip lever 27 projects well above the cylinder 20 and has attached to its upper end a suitable clevis or the like 29 to which is connected a pull line or trip cable 30. The opposite end of the cable 30 is attached in any suitable manner to the swinging lever 15 so that when the trip lever 27 is swung toward the cab 7, the lever 15 will be swung about its pivot and exert a pull upon the latch line 13.

Projecting upwardly from the forward closed or pressure end of the cylinder 20 is an apertured extension 31 for connecting one end of a contractile coil spring 32 having its opposite end suitably connected to the trip lever 27 above the pivot 26. Thus it will be seen that the return spring 32 acts to normally draw the trip lever toward the cylinder 20 and move the piston 24 into the cylinder.

Opening into the cylinder 20 adjacent its closed end wall 20' is an inlet port coupling 34 to which is connected a preferably flexible fluid pressure line 35 that extends to a control valve 36 arranged at any preferred location in the cab 7. The valve 36 may be an automatic return valve operated by foot pressure so that when released, flow to the cylinder 20 is automatically shut off. The pressure for operation of the tripping device may either be steam or compressed air in accordance with the particular type of power shovel to which the device is applied.

Connected at the pressure end of the cylinder 20 and in the example illustrated, in the end wall 20' is a pressure relief valve 38 for exhausting the cylinder after the tripping operation. This valve 38 may be in the form of a small drain cock and is adjusted so as to permit escape of the steam or air from the cylinder in sufficient time for the next tripping operation. The relief valve after once being properly adjusted is left in its adjusted open position to permit inward movement of the piston 24 by the spring 32. The opening thru the valve 38 is of course considerably smaller than the opening thru the inlet coupling 34 so that a pressure is formed in the cylinder for operating the piston when the control valve 36 is opened.

Secured to the lower end of the mounting plate 22 is an upstanding arm 40 having its upper end offset so as to be disposed directly rearward of and in the path of movement of

the trip lever 27. The upper end of this arm 40 is apertured as at 41 for receiving a threaded stem 42 on which are threaded bolts 43 adapted to be turned into binding engagement with the arm at opposite ends of the opening 41. These bolts 43 serve to permit longitudinal adjustment of the stem 42 which carries at its forward end a stop block or disc 44 to be engaged by the trip lever 27. This adjustable stop block 44 serves to limit movement of the trip lever by the piston 24 and may be adjusted to permit the proper limit of pull upon the trip cable 30.

In operation of the device for tripping the dipper bottom 11, the operator merely opens the control valve 36 by a pressure of the foot or hand as the case may be and allows steam or air to enter the cylinder 20. This pressure in the cylinder operates the trip lever 27 against tension of the spring 32 and exerts a pull on the trip cable 30 which in turn thru the swinging lever 15 and latch line 13 releases the latch holding the dipper bottom 11. As soon as the bottom 11 is tripped the operator releases the control valve 36, shutting off fluid pressure to the cylinder 20 and allowing pressure in the cylinder to escape thru the relief valve 38 and the trip lever to be returned by the spring 32.

Thus it will be seen that a simple and efficiently operating device of this character has been disclosed whereby the bottoms of power shovel dippers may be tripped by means of fluid pressure and with little or no manual effort upon the part of the operator. It will also be observed that the device is readily adaptable for use upon power shovels of conventional construction.

Changes in detail may be made to the form of invention herein shown and described, without departing from the spirit of the invention or the scope of the following claims.

I claim:

1. In fluid pressure operated trip means for dipper bottoms; a mounting plate, a cylinder mounted upon the outer end of the plate, a piston movable in the cylinder, a trip cable lever pivoted upon the plate rearwardly of the cylinder and projecting above the cylinder, a rod connecting the piston and lever for rearward swinging of the lever by the piston, a pressure inlet port opening into the forward end of the cylinder, means for controlling entrance of fluid thru the port, a bleeder valve for the forward pressure end of the cylinder, an adjustable stop mounted upon the plate rearwardly of the trip lever for limiting rearward swinging movement of the lever, an apertured extension at the forward end of the cylinder, and a contractile coil spring connected between the extension and trip lever for returning the lever toward the cylinder.

2. In a power dipper trip of the class de-
